CLAIM

The ornamental design for the dermaplaning razor, as shown and described.

DESCRIPTION

FIG. 1 is an upper rear perspective view of the first embodiment of a dermaplaning razor.

FIG. 2 is an upper front perspective view thereof.

FIG. 3 is a top view thereof.

FIG. 4 is a bottom view thereof.

FIG. 5 is a front view thereof.

FIG. 6 is a rear view thereof.

FIG. 7 is a side view thereof.

FIG. 8 is an opposed side view of FIG. 7.

FIG. 9 is an upper rear perspective view of the second embodiment of a dermaplaning razor of FIG. 1 shown with a Protective Overcap.

FIG. 10 is an upper front perspective view of the dermaplaning razor of FIG. 9.

FIG. 11 is a top view of the razor of FIG. 9.

FIG. 12 is a bottom view of the razor of FIG. 9.

FIG. 13 is a front view of the razor of FIG. 9.

FIG. 14 is a rear view of the razor of FIG. 9.

FIG. 15 is a side view of the razor of FIG. 9; and,

FIG. 16 is an opposed side view of FIG. 15.

The broken lines in the figures are for the purpose of illustrating portions of the dermaplaning razor and form no part of the claimed design.
